SWIMMING POOL COPING

Robert Donald Robb, 1942 Marconi Ave.,
Sacramento, Calif.

Filed Sept. 8, 1964, Ser. No. 81,642

Term of patent 14 years

(Cl. D13—1)

FIG. 1.

FIG. 2.

FIG. 3.

FIG. 4.

FIGURE 1 is an isometric view of a swimming pool coping, showing my new design, the broken line showing of inset tiles being for illustrative purposes only;

FIGURE 2 is a front elevational view thereof;

FIGURE 3 is a plan view thereof; and

FIGURE 4 is an end elevational view thereof.

I claim:

The ornamental design for a swimming pool coping, as shown and described.
